Primary Examiner — Steven J Czyz

(74) Attorney, Agent, or Firm — Thomas Horstemeyer,
 LLP(57) **CLAIM**

The ornamental design for a floor lamp, as shown and described.

DESCRIPTION**1.1** is a perspective view of a floor lamp, showing my new design;**1.2** is a front view thereof;**1.3** is a rear view thereof;**1.4** is a left view thereof;**1.5** is a right view thereof;**1.6** is a top view thereof; and**1.7** is a bottom view thereof.

The floor lamp is shown with a symbolic break in its length. The appearance of any portion of the article between the break lines forms no part of the claimed design. The broken lines shown in the drawings of the floor lamp form no part of the claimed design.
